UNITED STATES PATENT OFFICE

148,761

DESIGN FOR A ROCKET CAR

James Carmody, Collingswood, N. J.

Application November 14, 1946, Serial No. 134,768

Term of patent 3½ years

(Cl. D34—15)

To all whom it may concern:

Be it known that I, James Carmody, a citizen of the United States, residing at Collingswood, in the county of Camden and State of New Jersey, have invented a new, original, and ornamental Design for Rocket Cars, of which the following is a specification, reference being had to the accompanying drawing, forming a part thereof, in which—

Fig. 1 is a perspective view of a rocket car, showing my new design.

Fig. 2 is a rear end view thereof.

Fig. 3 is a front end view of the same.

Fig. 4 is a top plan view thereof.

Fig. 5 is a side elevation thereof.

I claim:

The ornamental design for a rocket car, as shown.

JAMES CARMODY.
